UNITED STATES PATENT OFFICE.

JENNINGS SCOTT McCOMB, OF DOBBS FERRY, NEW YORK

LOOSE-LEAF BINDER.

940,706.

Specification of Letters Patent. Patented Nov. 23, 1909.

Application filed June 8, 1908. Serial No. 437,427.

To all whom it may concern:

Be it known that I, JENNINGS SCOTT McCOMB, a citizen of the United States, and a resident of Dobbs Ferry, in the county of 5 Westchester and State of New York, have invented certain new and useful Improvements in Loose-Leaf Binders, of which the following is a specification, taken in connection with the accompanying drawings, which 10 form a part of the same.

This invention relates to loose leaf binders and more particularly to sectional posts or pillars for such binders and means for readily attaching and detaching the different 15 sections.

It also relates to supports or disks which may form a part of the posts or pillars and which may be used to support a portion of the contents of the loose leaf binders and 20 also, if desired, form a rear index.

In the accompanying drawings showing 25 illustrative embodiments of this invention, and in which the same reference numerals refer to similar parts in the several figures, Figure 1 is a longitudinal vertical section of a loose leaf binder equipped with my invention. Fig. 2 is a side elevation of two of the sections of the post in position to be assembled. Fig. 3 is a plan view of a support 30 or disk which may be used with a post or pillar of a loose leaf binder. Fig. 4 is a side elevation of the support or disk shown in Fig. 3. Fig. 5 is a fragmentary plan view of one of the loose leaf sheets to be 35 used in the binder. Fig. 6 is a side elevation, partly in vertical section of a modified form. Fig. 7 is a side elevation of a section similar to that shown in Fig. 6.

In the illustrative embodiments of my invention shown in the drawing 1 is a loose leaf binder having a back 2, cover 3 and loose leaf pages 4 and an extensible pillar or post 5. As is usual in such binders, the pillars or posts 5, only one being shown in 45 the drawing, are made in sections so as to be extensible to increase or decrease the length of the post and consequently, increase or decrease the capacity of the loose leaf binder 1. By my invention I form the 50 pillar or post 5 of section 6, 6 having a tongue 7 mounted at one end and a pin 8 mounted at the other end of the section, the pin adapted to be seated in a socket 9 in a detachable section 6 and the tongue 7 being 55 adapted to coöperate with a screw thread 10, preferably of coarse pitch, a slot 11 being

formed in the tongue 7 to approximately fit the thread 10. The pitch of the thread 10 is preferably so formed that when for instance a pin 8 is placed in the socket 9 and the screw thread 10 in the slot 11, Fig. 2, one complete revolution of one of the sections, for example the upper section, will cause the pin 8 to be seated in the socket 9 and securely lock the parts together. 65

The different sections 6, 6 are made of sufficiently small diameter to fit an opening 12 in the sheets 4. These openings 12 may be formed sufficiently large to receive the tongue 7, or in some cases these tongues may be permitted to lie between the walls 13, 13 of the filing slot 14 in the sheets 4, Fig. 5. In some instances, I may use a support or disk 15, Figs. 3 and 4. These supports form an integral portion of the pillar or post and 75 serve to support the loose leaves at intervals throughout the binder, it being understood that one or a plurality of such supports 15 may be used. By using my supports 15, the unnecessary labor of threading a great 80 number of sheets 4 on and off the pillars 5 is avoided when a new leaf is to be inserted in the binder or an old one removed. When the pillar 5 is equipped with these supports or disks 15, the position in the binder is 85 determined where it is desired to insert or remove a sheet and the two sections 6, 6 nearest this point in the binder, are disconnected by rotating one section upon the other. The support or disk 15 which happens to be immediately above the section 16 of the post 5 which is disconnected, will 90 support the loose leaves or sheets and permit their ready removal temporarily with the cover 2 until a new sheet is added or an old one removed. To assist in determining approximately where the pillars 5 should be disconnected, I may place index numerals or letters upon the supports 15. I have shown in Fig. 3 for instance the letters AA 95 which may correspond with those upon the front index (not shown), one support or disk being used for each letter of the index, or for any multiple thereof. These supports or disks have a substantially cylindrical 100 portion 16, a pin 17 similar to the pins 8 of the sections 6, a socket 18 for the reception of a pin 8, and are provided also with a tongue 19 having a slot 20 to coöperate with a screw thread 10, a similar screw 105 thread 21 being developed upon the exterior surface of the cylindrical portion 16. These

110

disks are connected to the section 6 in substantially the same manner as the different sections 6, 6 are connected to each other, Fig. 2.

- 5 In some instances, I may develop the coarse pitch screw thread upon the interior of the sections. For instance in Fig. 6, I may have a section 22 with a reduced portion 23 at one end provided with a lug 24. 10 The other end of the section may be tapped and provided with a female screw thread 25 adapted to coöperate with a lug 24 of a complementary section 22, Fig. 7. In this modification the two sections 22, 22 are 15 connected together by inserting lug 24 in the opening 26 of a complementary section and then giving one of the sections a complete turn causing the lug 24 to travel in the female screw thread 25 and bind the parts 20 securely together.

Having thus described this invention in connection with several illustrative embodiments thereof, to the details of which I do not desire to be limited, what is claimed as new and what it is desired to secure by Letters Patent is set forth in the appended claims.

1. An extensible post for loose leaf binders formed of a plurality of sections, each 30 section provided with means for locking the sections together upon one complete revolution of the sections.

2. An extensible post for loose leaf binders formed of a plurality of sections, each 35 section provided with means for locking the sections together upon one complete revolution of the sections and a support or disk provided with means to coöperate with the sections of the pillar or post.

40 3. An extensible pillar or post for loose leaf binders provided with different detach-

able sections, each section provided with a screw thread and with a tongue to coöperate with the complementary screw thread.

4. An extensible pillar or post for loose 45 leaf binders provided with different detachable sections, each section provided with a screw thread and with a tongue to coöperate with the complementary screw thread and a support or disk provided with similar 50 tongues and screw threads to coöperate with tongues and screw threads upon the sections of the post.

5. A section for an extensible post or pillar for loose leaf binders having a body 55 portion, a pin at one end of the body portion, a tongue and socket at the other end of the body portion and a screw thread.

6. A section for an extensible post or pillar for loose leaf binders comprising a 60 substantially cylindrical body portion, an axial pin at one end of the body portion, an axial socket at the other end of the body portion, a notched tongue secured to the body portion and a coarse pitch screw thread 65 developed on the exterior surface of the body portion.

7. A support or disk for extensible posts for loose leaf binders comprising a body portion of substantially the same shape or 70 contour as the sections of the post, a pin located at one end of the body portion, the other end of the body portion being enlarged to form a support and provided with a socket, a tongue carried on the enlarged portion of the support and a coarse pitch screw 75 thread developed on the body portion.
